UNITED STATES PATENT OFFICE.

FRANK E. SHAILOR, OF DETROIT, MICHIGAN, ASSIGNOR TO FRANK KUHN, OF DETROIT, MICHIGAN.

CONNECTOR-PLUG FOR ELECTRICAL INSTRUMENTS.

1,130,935.

Specification of Letters Patent.

Patented Mar. 9, 1915.

Application filed October 25, 1913. Serial No. 797,187.

To all whom it may concern:

Be it known that I, FRANK E. SHAILOR, a citizen of the United States of America, residing at Detroit, in the county of Wayne and State of Michigan, have invented certain new and useful Improvements in Connector-Plugs for Electrical Instruments, of which the following is a specification, reference being had therein to the accompanying drawings.

The invention relates to connectors for electrical instruments, such as used for electrically-heated sad irons and similar devices, and it is the object of the invention to provide means for guiding the plug into engagement with the terminal contacts, as well as releasing the latter from mechanical stresses.

To this end the invention comprises the construction as hereinafter set forth.

20 In the drawings: Figure 1 is a perspective view of an electrically-heated sad iron with the improved connector applied thereto; Fig. 2 is a cross section through the plug and guide; Fig. 3 is a side elevation of Fig. 1, showing the parts in engaged position; and Fig. 4 is an elevation of the guide showing a modified construction.

A is the casing of the sad iron or other instrument to be heated. B is the handle therefor, which, as shown, is attached to the casing by metallic arms or brackets C and C'.

D are the terminal contacts projecting outward from the case in rear of the bracket C, and E is the connector plug for engaging 35 with said contacts.

To guide the plug while being engaged with the contacts and also to hold it in engaged position, so as to relieve stress from said contacts, I have formed upon the side 40 of the plug and preferably upon each side as shown in Fig. 2 parallel flanges F, which are adapted to engage the opposite edges of the arm or bracket C. This arm is therefore formed with a portion G which is parallel 45 to the contacts D, and a bent portion H extending to the handle. Adjacent to the bend the portion H is cut away at its opposite edges, as indicated at I, so as to provide clearance for the engagement of the flanges 50 F with the portion G.

To securely fasten the flanges F to the

plug, and also to increase the strength of the latter, a metallic strap J is bent to embrace the insulator body K and to extend downward upon opposite sides thereof. This strap is provided with ears from which the 55 flanges F are struck up, while screws L, passing centrally through the body and the opposite sides of the strap, clamp the parts in fixed position.

The guides F are preferably formed upon 60 opposite sides of the plug, so that the latter is reversible and in either position may be engaged with the guide G.

As shown in Fig. 4, the guide portion G of the handle supporting arm or bracket may 65 be formed with struck-out ears G' for engagement with the flanges F. This avoids necessity of cutting away the bracket at the bend and permits of the free engagement and disengagement of the guides.

70 What I claim as my invention is:

1. The combination with an electrically-heated instrument of a terminal contact therefor, a handle bracket extending parallel to said contact, and a detachable connector 75 plug slidably interlocking directly with said parallel portion of said brackets to be guided thereby into engagement with said terminal contact.

2. The combination with an electrically-heated instrument, of a terminal contact projecting therefrom, a handle bracket extending parallel to said contact, an insulator connector plug, and a metallic guide upon said plug slidably engageable with the parallel handle bracket, to be guided thereby 80 into engagement with said terminal contact.

3. The combination with an electrically-heated instrument of a terminal contact projecting therefrom, a handle bracket having a portion extending parallel to said contact and a bent portion for attachment to the handle, a plug connector, and guides upon said connector for embracing the parallel portion of said handle bracket to guide said 90 plug into engagement with said terminal contact.

4. The combination with an electrically-heated instrument of a terminal contact projecting therefrom, a handle bracket having a portion extending parallel to said con- 100

tact, a plug connector and guides on opposite sides of said plug for alternative engagement with said parallel portion of the bracket to guide said plug into engagement with said terminal contact.

5. The combination with an electrically-heated instrument of a terminal contact projecting therefrom, a handle bracket having a portion extending parallel to said terminal contact, an insulator connector plug, a metallic strap embracing said plug, and guides struck-up from opposite sides of said strap for alternatively engaging said parallel portion of the handle bracket to guide said plug into engagement with said terminal contact.

6. The combination with an electrically-heated instrument of a terminal contact projecting therefrom, a handle bracket formed of a flat bar having a portion extending parallel to said terminal contact and a bent portion for connecting with the handle, the opposite sides being narrower at the bend, and a terminal plug provided with spaced guides for embracing the opposite edges of said parallel portion of the handle bracket and adapted to enter into engagement therewith over the narrower bent portion thereof.

7. The combination with an electrically-heated instrument of a pair of terminal contacts projecting therefrom, a handle bracket formed of a flat bar having a portion extending parallel and adjacent to said terminal contacts, with a bent portion extending to the handle and narrower at the bend than said parallel portion, and a connector plug having hooked guide flanges for embracing the opposite edges of said parallel portion of the handle bracket and engageable therewith at said narrower bend.

8. The combination with an electrically-heated instrument of a terminal contact projecting therefrom, a handle bracket formed of a flat bar having a portion extending parallel to said terminal contact and a bent portion for connecting with the handle, the opposite sides of said parallel portion being struck-out to increase the width, and a terminal plug provided with spaced guides for embracing the struck-out opposite edges of said parallel portion and adapted to enter into engagement therewith over the narrower portion at the bend.

9. In an electric laundry-iron, a body; a standard arranged over the rear portion of and secured to said body and instrumental in supporting a grip-member; two laterally spaced terminal pins rearward of and spaced from the lower portion of said standard and extending upwardly from and secured to the body; a terminal plug slipped onto and movable upwardly from the pins, and a plate arranged at the rear face of and secured to said plug and provided with two arms ar-

ranged at opposite sides respectively of the plug and having members extending over the forward side of said standard, the standard being contoured and arranged to permit movement of said arms upwardly from the standard during removal of the plug from the pins.

10. In an electric laundry-iron, a body; an approximately U-shaped handle-supporting member arranged over and longitudinally of and secured to said body, the end portions of said U-shaped member forming upwardly diverging standards; a grip-member extending between the upper ends of and secured to said standards; two laterally spaced terminal pins arranged rearward of and spaced from and substantially parallel with the lower portion of the rear standard and extending upwardly from and secured to the body; a terminal plug slipped onto and movable upwardly from the pins, and a plate arranged at the rear face of and secured to said plug and provided with two arms arranged at opposite sides respectively of the plug and having members overlapping the forward side of the rear standard, the rear standard being contoured and arranged to permit movement of said arms upwardly from said standard during removal of the plug from the pins.

11. In an electric laundry-iron, a body; two laterally spaced terminal pins projecting upwardly from the top of the rear portion of and secured to the body; a standard arranged over said portion of and secured to the body and having a portion which is substantially parallel with and arranged forward of and spaced from said pins, which standard is provided above said pins with a forwardly projecting portion terminating at its forward end in a member which is instrumental in supporting a grip-member, said standard being provided at each side edge thereof with a recess extending from end to end of said forwardly projecting portion of the standard; a terminal plug slipped onto and movable upwardly from said pins, and a plate carried by said plug and having two arms which are arranged below the said forwardly projecting portion of the standard and extend over the front side of the standard, the free ends of said arms being arranged to permit said ends to pass through the aforesaid recesses.

12. In an electric laundry-iron, a body; a rearwardly slanting standard arranged over the rear portion of and secured to the body, which standard is provided with a forwardly projecting portion spaced from the lower end of the standard and terminating at its forward end in a member instrumental in supporting a grip-member; a terminal plug arranged at the rear side of said standard, and a plate carried by said plug and

having two arms which are arranged below said forwardly projecting portion of said standard and overlap opposite side edges respectively of the standard and extend over the front side of the standard, the aforesaid forwardly projecting portion of the standard having the arrangement and dimensions required to permit movement of said arms

upwardly from the standard during removal of the plug from the standard.

10

In testimony whereof I affix my signature in presence of two witnesses.

FRANK E. SHAILOR.
